(57) **CLAIM**

The ornamental design for an ice pack holder, as shown and described.

DESCRIPTION

FIG. 1 shows a top plan view of the ice pack holder in an unfolded configuration.

FIG. 1 shows a perspective view of the ice pack holder.

FIG. 2 shows a front elevation view of the ice pack holder.

FIG. 3 shows a rear elevation view of the ice pack holder.

FIG. 4 shows a right side elevation view of the ice pack holder.

FIG. 5 shows a left side elevation view of the ice pack holder.

FIG. 6 shows a top plan view of the ice pack holder; and, FIG. 7 shows a bottom plan view of the ice pack holder. The broken lines shown in the drawings represent environmental effects and do not form any part of the claimed design.

The shade lines in the drawings show contour and not surface ornamentation.
